UNITED STATES PATENT OFFICE

155,282

DESIGN FOR AN ELECTRIC ORGAN

Paul M. Fuller, Buffalo, N. Y., assignor to The Rudolph Wurlitzer Company, North Tonawanda, N. Y., a corporation of Ohio

Application July 22, 1947, Serial No. 140,447

Term of patent 7 years

(Cl. D56—9)

To all whom it may concern:

Be it known that I, Paul M. Fuller, a citizen of the United States, residing at Buffalo, Erie County, New York, have invented a new, original, and ornamental Design for an Electric Organ, of which the following is a specification, reference being had to the accompanying drawing, forming a part thereof:

Fig. 1 is a front perspective view of an electric organ, showing my new design, with the keyboard cover in closed position and the music rack retracted; and

Fig. 2 is a front view of the electric organ shown in Fig. 1, with the keyboard cover open and the music rack in extended position.

The bench structure is indicated in dotted lines for illustrative purposes only.

I claim:

The ornamental design for an electric organ, substantially as shown and described.

PAUL M. FULLER.
